CLAIM

The ornamental design for a toothbrush, as shown and described.

DESCRIPTION

FIG. 1 is an enlarged $\frac{3}{4}$ perspective view of a toothbrush showing our new design;
FIG. 2 is a top plan view thereof;
FIG. 3 is a bottom plan view thereof;
FIG. 4 is a left side elevational view thereof;
FIG. 5 is a right side elevational view thereof;
FIG. 6 is a view from the head end thereof;
FIG. 7 is a view from the handle end thereof;
FIG. 8 is an enlarged $\frac{3}{4}$ perspective view of a second embodiment of the toothbrush showing our new design;
FIG. 9 is a top plan view thereof;
FIG. 10 is a left side elevational view thereof;
FIG. 11 is a right side elevational view thereof;
FIG. 12 is a view from the head end thereof;
FIG. 13 is a view from the handle end thereof;
FIG. 14 is an enlarged $\frac{3}{4}$ perspective view of a third embodiment of the toothbrush showing our new design;
FIG. 15 is a top plan view thereof;
FIG. 16 is a left side elevational view thereof;
FIG. 17 is a right side elevational view thereof;
FIG. 18 is a view from the head end thereof;
FIG. 19 is a view from the handle end thereof;
FIG. 20 is an enlarged $\frac{3}{4}$ perspective view of a fourth embodiment of the toothbrush showing our new design;
FIG. 21 is a top plan view thereof;
FIG. 22 is a left side elevational view thereof;
FIG. 23 is a right side elevational view thereof;

FIG. 24 is a view from the head end thereof;
FIG. 25 is a view from the handle end thereof;
FIG. 26 is an enlarged $\frac{3}{4}$ perspective view of a fifth embodiment showing a handle of our toothbrush design, with the broken line showing of bristles being for illustrative purposes only and forming no part of this embodiment;
FIG. 27 is a top plan view thereof;
FIG. 28 is a left side elevational view thereof;
FIG. 29 is a right side elevational view thereof;
FIG. 30 is a view from the head end thereof;
FIG. 31 is a view from the handle end thereof;
FIG. 32 is an enlarged $\frac{3}{4}$ perspective view of a sixth embodiment showing a handle of our toothbrush design, with the broken line showing of bristles being for illustrative purposes only and forming no part of this embodiment;
FIG. 33 is a top plan view thereof;
FIG. 34 is a bottom plan view thereof;
FIG. 35 is a left side elevational view thereof;
FIG. 36 is a right side elevational view thereof;
FIG. 37 is a view from the head end thereof;
FIG. 38 is a view from the handle end thereof;
FIG. 39 is an enlarged $\frac{3}{4}$ perspective view of a seventh embodiment of the toothbrush showing our new design;
FIG. 40 is a top plan view thereof;
FIG. 41 is a left side elevational view thereof;
FIG. 42 is a right side elevational view thereof;
FIG. 43 is a view from the head end thereof; and,
FIG. 44 is a view from the handle end thereof.
The bottom plan view embodiments 2, 3, 4, 5, and 7, is the same in appearance as the bottom plan view that is shown in FIG. 3.
